UNITED STATES PATENT OFFICE.

JOHN SACHAR, OF KATO, PENNSYLVANIA, ASSIGNOR OF ONE-HALF TO ANTONINE ULANITZKI, OF SHENANDOAH, PENNSYLVANIA.

AEROPLANE-DESTROYING GUN.

1,200,034.

Specification of Letters Patent.

Patented Oct. 3, 1916.

Application filed July 12, 1916. Serial No. 108,861.

To all whom it may concern:

Be it known that I, JOHN SACHAR, a subject of the Emperor of Austria-Hungary, residing at Kato, in the county of Center 5 and State of Pennsylvania, have invented certain new and useful Improvements in Aeroplane-Destroying Guns, of which the following is a specification.

The primary object of the invention is 10 the provision of a gun adapted for destroying air crafts such as aeroplanes and war balloons, the same being provided with an armored truck adapted for conveying the gun to an accessible point for firing without 15 endangering the artillerymen from flying missiles.

A further object of the device is to provide a gun having a mounting means upon 20 an armored truck, the mounting means being capable of shifting the gun in any desired direction and at any vertical angle that may be required.

A still further object of the device is to provide a truck having an adjustable gun 25 carriage mounted thereon, the said truck being provided with armored sides readily adjusted from an inclosing position to their open separated positions when desired for upwardly firing the gun mounted upon the 30 carriage.

With these general objects in view and others that will appear as the nature of the invention is better understood, the same consists in the novel combination and arrangement of parts hereinafter fully described, 35 illustrated in the accompanying drawings and then claimed.

In the drawings forming a part of this application and in which like designating 40 characters refer to corresponding parts throughout the several views:—Figure 1 is an elevational view of the device with portions of the truck shown in vertical longitudinal section with one of the armored 45 sides removed. Fig. 2 is a rear elevational view of the same in its open position with portions of the armored sides broken away. Fig. 3 is a vertical transverse sectional view through the truck with one of the armored 50 sides closed and the other in its open position. Fig. 4 is a view similar to Fig. 3 with

parts broken away illustrating the adjustable bracing means for the armored sides of the truck. Fig. 5 is a detail view showing the inner face of the rear axle block, and 55 Fig. 6 is an elevational view of a side portion of the gun mount with the gun partially broken away.

The present invention broadly contemplates the provision of a truck 10 having a 60 platform 11 mounted upon wheels 12, the said platform being provided with opposite armored inclosing sides 13 hinged thereto for the protection of a gun 14 mounted upon an adjustable carriage 15 carried by 65 the platform 11 as well as for the protection of the soldiers having charge of the said fire-arm. The gun carriage comprises a base 16 in the form of a disk having a plurality of depending legs 17 in each of which 70 a roller 18 is journaled for running upon a circular track 19, the said legs 17 having depending hooks 20 for engaging within an annular groove 20 peripherally arranged in the said track, the latter being secured, flatly 75 positioned, upon the truck platform 11 with the center of the said track directly over the supporting block 22 of the rear axle 23. Opposite parallel vertical sides 24 are provided for the gun mount positioned upon 80 the base 16 and connected together by braces 24', the gun 14 being pivotally mounted upon the sides 24 by means of a shaft 25.

A central depending shaft 26 is carried by the base 16 having a pinion 27 mounted 85 on the lower end thereof within a cut away portion 28 of the rear axle block 22. An operating shaft 29 is centrally arranged journaled beneath the rear end of the platform 11 having a pinion 30 in constant mesh 90 with the said pinion 27 and arranged with a hand wheel 31 at the rear of the truck. It will thus be evident that by turning the wheel 31 in the required direction, the disk 16 and gun 14 may be revolved as found 95 desirable.

The gun shaft 25 is provided with a gear 32 upon one end thereof in constant mesh with a gear 33 carried by the adjacent side 24 of the gun mount and arranged with a 100 relatively smaller stub gear 34 adapted to be engaged by a retaining hook 35 operated

by a hand knob 36 at the opposite side of the gun mount 15. A gear 37 is carried by the shaft 25 at the opposite side thereof from the gear 32 in constant mesh with a 5 gear 38 carried by the adjacent side 24 of the gun mount while an operating lever 39 is arranged for ratcheting engagement with the gear 38. By means of the lever 39, the shaft 25 and gun 14 may be turned as found 10 desirable when the hook 35 is released by means of the handle 36 and when the gun 14 is arranged at the proper vertical angular adjustment the handle 36 is operated for engaging the hook 35 with the stub gear 34 15 for retaining the gun adjusted.

The truck 10 may be propelled in any desired manner and may be in the form of a motor truck if desired. A forwardly inclined curved hood 40 is preferably arranged 20 after the manner of a bullet shield being provided with a serviceable view port 41 while an ammunition case 42 upon the platform 11 has the lid 43 thereof arranged as a seat for the artillerymen. Steps 44 are arranged 25 at the rear of the platform 11 at opposite sides of the carriage mount adjusting wheel 31.

The armored sides 13 are provided with curved metallic side plates 45 and are hinged 30 as at 46 to the opposite edges of the platform 11 being provided with closed rear ends 46' and with forward closing plates 47, the latter fitting over the hood 40, whereby when the sides 13 are closed the gun 14 35 and everything mounted upon the platform 11 is fully protected against bullets and any flying missiles. Upright posts 48 are carried by the platform 11 adapted for engagement by the sides 13 when the latter are 40 closed, staples 49 being carried by the said sides projecting through perforations 50 in the said posts adapted to be engaged by pins 51 carried by the said posts and whereby the sides 13 are retained in their closed 45 positions.

Braces 52 are hinged to the sides 13 as at 53 adapted to be retained inoperative by means of spring clips 54 when the said sides are closed. The said braces 52 are provided 50 with hooks 55 at their free ends adapted for adjustable engagement with toothed racks 56 carried by the platform 11 when the sides 13 are swung outwardly and downwardly in their partially or completely 55 opened positions. Operating levers 57 are provided for the sides 13 pivoted to racks 58 carried by the platform 11 and extending through perforations 59 in the said platform, the lower ends of the said levers 57 60 being pivotally attached to the lower ends of the arms 60 of the sides 13 by means of links 61, it being noted that the upper ends of the arms 60 are rigidly connected to the sides 13. Spring pressed catch bars 62 are

carried by the levers 57 adapted for engagement within notches 63 of the racks 58 for maintaining the levers 57 and the sides 13 in their adjusted positions.

From this detailed description of the entire device, it will be understood that the 7 sides 13 being closed, the truck 11 is propelled to position the gun 14 within shooting range of the aeroplane or air craft to be destroyed. When such position is gained, the levers 57 will be actuated upon releasing the securing pins 51 and the sides 13 separated and lowered to the desired degree and retained in their adjusted positions by means of the braces 52 and bars 62. The gun 14 may be then readily operated by 8 turning in the desired direction by means of the wheel 31 and tilted at the desired vertical angle by means of the lever 39 as hereinbefore described. The sides 13 when completely opened as best illustrated in Fig. 2 8: of the drawings form side extensions for the platform 11 although it is unnecessary to completely open the same for the usual firing of the gun 14 upwardly while the gun may be employed for shooting at one side of 90 the truck when one of the members 13 is opened as best illustrated in Fig. 3 while the other side then forms a bullet guard or protector.

What I claim as new is:—

1. A device of the class described comprising a wheel truck having a platform, an adjustable gun carriage mounted upon the said platform, a forwardly inclined curved bullet deflecting hood arranged forwardly of the said truck having a sight opening therein, armored sides hinged to the opposite edges of the said platform having curved bullet deflecting plates, manual tilting means for the said sides and adjustable retaining braces for the latter.

2. A device of the class described comprising a wheel truck having a platform, a circular track upon the said platform, a disk base shiftably arranged upon the said track, 11: revolving means for the said base operable rearwardly of the said platform, a gun pivotally arranged upon the said base, an adjustable tilting means for the said gun, a forwardly inclined curved bullet deflecting 11: hood arranged forwardly of the said truck having a sight opening therein, armored sides hinged to the opposite edges of the said platform having curved bullet deflecting plates, manual tilting means for the 120 said sides and adjustable retaining braces for the latter.

3. A device of the class described comprising a wheel truck having a platform, a bullet deflecting hood forwardly arranged 125 thereon, curved armored inclosing sides pivoted to the opposite edges of the said platform, adjustable retaining braces for the

said sides, depending arms carried by the said sides, operating levers pivoted upon the said platform linked to the said arms and locking devices carried by the said levers.

- 5 4. A device of the class described comprising a platform, a base revolvably mounted thereon, an operating wheel for the said base positioned rearwardly of the said platform, a gun mount positioned upon the said base,

a gun journaled transversely in the top of 10 the said mount, a shifting lever for the said gun at one side of the said mount and a retaining hook for the gun at the opposite side of the said mount operable adjacent the said operating lever.

In testimony whereof I affix my signature.

JOHN SACHAR.
